UNITED STATES PATENT OFFICE.

ALBERT A. HUSEBY, OF CHICAGO, ILLINOIS.

PNEUMATIC STRIKER ACTION FOR PLAYER PIANOS.

Application filed August 23, 1924. Serial No. 733,672.

This invention relates to pneumatic striker actions for player pianos and other self-playing musical instruments, and has for its general object to simplify the construction, 5 reduce the number of parts and consequently the liability of leakage, lessen the cost of manufacture, and reduce the space required by the structure. Other more specific objects are, to provide an improved semi-unit 10 action which will facilitate the making of repairs and renewals, to provide an improved construction of valve board which will contain not only the valve chambers and valves but also the air channel, to provide an improved 15 striker pneumatic unit that may be removably attached to the under side of the valve board and shall contain in its stationary side the usual valve motor diaphragm or pouch and the pressure and vacuum ducts 20 thereto from the tracker range tube and the air channel respectively, to provide an improved closing strip for the air channel, and to provide an improved bleed vent for the under side of the valve pouch.

25 Other objects and attendant advantages of the invention will be apparent to persons skilled in the art as the same becomes better understood by reference to the following detailed description, taken in connection with 30 the accompanying drawing in which I have illustrated one practical embodiment of the invention, and wherein—

Fig. 1 is a vertical transverse section through the action on the line 1—1 of Fig. 35 2; and

Fig. 2 is a top plan view of a fragment of the valve board and underlying striker pneumatics.

Referring to the drawing, 5 designates as 40 an entirety the valve board which extends the full length of the complete action and is preferably and as shown formed from a single board of suitable thickness vertically chambered at intervals at substantially its 45 transverse center to form valve chambers 6. Through one edge of the board (the left as shown in Fig. 1) are bored round ducts 7, the inner ends of which communicate with the valve chambers 6, and the outer ends of 50 which are closed by a continuous sealing strip 8 glued to the edge of the valve board. On the other side of the valve chambers 6 the opposite edge of the board is recessed to form a continuous air channel 9, the outer 55 edge of which is sealed by a wooden closing strip 10 glued thereto and preferably formed

on its inner face with a shallow tongue 11 which enters the channel 9 and maintains the outer edges of the side walls thereof in rigid spaced relation. Through the bottom of the 60 valve board are formed a series of short vertical ducts 12, each of which communicates at its upper end with one of the horizontal ducts 7.

The valve chamber 6 is equipped with the 65 usual upper and lower valve seats 13 and 14, respectively, for co-operation with the usual mushroom valve 15, the spider-shaped stem 16 of which extends downwardly through a guide opening 17 in the bottom wall of the 70 valve chamber 6, and is stepped upon the usual valve motor diaphragm or pouch 18.

The air channel 9 communicates with the suction bellows or reservoir of the instrument so that, while the latter is played, a 75 partial vacuum is maintained in the air channel; and through the bottom wall of the air channel are formed a series of circular 80 openings 19 one for each underlying pneumatic.

Glued to the entire under side of the valve board 5 is a paper strip or gasket 20, formed with openings registering with the several bottom openings 12, 17 and 19 of the valve board. Glued to the under side of the gasket 20 in lateral juxtaposition are the striker 85 pneumatic units, each embodying the structural features illustrated in the sectional view, Fig. 1. Describing one of these units, 21 designates as a whole a rectangular block 90 of substantially triangular form in longitudinal vertical section and of a depth or thickness sufficient to permit the formation therein of the chambers and ducts that house and control the valve pouch 18; said block 95 21 constituting the stationary side or fixed wall of the striker pneumatic. To the lower side of the wide end of the block 29 is hinged at 22 the movable wall 23 of the striker pneumatic, its free end being connected by the usual bellows cloth 24 to the corresponding 100 end of the stationary wall 21, and having attached thereto the usual striker arm 25. Through the block 21 is formed a vertical duct 26 that registers with the short 105 vertical duct 12 in the valve board, and thereby places the interior of the pneumatic in continuous communication with the valve chamber 6.

In the upper face of the block 21 is formed 110 a circular suction chamber 27 concentric with and surrounding the valve stem 16, and

directly therebeneath is another smaller circular pouch chamber 28. The diaphragm 18 separates the chambers 27 and 28, being attached at its edges to the annular shoulder 29 formed at the junction of the differential chambers 27 and 28. The upper chamber 27 is formed with a radial extension 30, the outline form of which is shown in Fig. 2 that underlies and registers with a portion of the 10 circular opening 19 into the air channel 9. Through the wide end of the block 21 is bored a horizontal duct 31, the outer end of which is closed by a screw plug 32 and washer 33. The inner end of the duct 31 communicates with the air channel 9 through a vertical duct 34 that, at its upper end, communicates with the circular opening 19 in the bottom wall of the air channel. From the inner end of the duct 31 a smaller horizontal duct 36 leads into the pouch chamber 28, and the outer end of this duct 36 is closed by a thimble cap or plug 37 formed with a central bleed hole 38. 39 designates the tube leading from the tracker range, the 20 lower horizontal end of which is entered into the wide end of the block 21 at one side of the duct 31, and communicates with a horizontal duct 40 that leads tangentially into the pouch chamber 28.

30 The broad operative principle of the apparatus described is the same as that of the standard single valve pneumatic striker action. The air channel 9 is, as stated, in communication with the suction bellows or reservoir of the player action through connections well known in the art and not necessary to be shown, so that a state of partial vacuum continuously exists in said channel. This vacuum acts on the upper side of the pouch 18 through the opening 19, chamber extension 30 and chamber 27, and also upon the lower side of the pouch through the opening 19, ducts 34 and 31, bleed hole 38 and duct 36, so that the valve 15 normally 40 occupies the position shown in Fig. 1. When the tracker opening to which the tube 39 is connected is opened by the music sheet, atmospheric pressure is admitted to the chamber 28, lifting the pouch 18, closing valve 15 on its upper seat 13 and raising it from its lower seat 14. This shuts off atmospheric pressure from the interior of the striker pneumatic and places the latter in communication with the air channel 9, causing 50 the striker pneumatic to collapse. Upon the closure of the tracker opening, the suction in air channel 9 acting through the bleed duct 38 restores the pouch chamber 28 to the same tension as chamber 27, whereupon 55 the valve drops to its normal position.

60 From the foregoing it will be seen that substantially the lower half of the complete action constitutes a bodily removable unit, so that the entire action may properly be defined as of a semi-unitary character. While

the invention involves no novel principle of operation, certain novel structural features thereof present distinct advantages particularly in regard to economy of manufacture and maintenance, and simplicity and compactness of structure which lessen the liability of leakage and require less space in the instrument, and facility of repairs and renewals. For instance, it will be observed that the valve chambers, the air channel, and the horizontal ducts connecting the valve chambers with the interior of the pneumatic are all formed in a single integral board, thereby eliminating a large number of glued joints heretofore employed for the assembling of these parts; my improved valve board having only marginal joints formed by the closing strips 8 and 10. By fastening the pneumatics to the bottom of the valve board by a single glued joint, each pneumatic can obviously be removed when necessary without disturbing the others or otherwise disassembling the complete action; and in facilitating such removal of a pneumatic unit from the bottom of the valve board, the presence of the paper gasket is important, since in the withdrawal of the pneumatic by downward pressure at one end, the paper of the gasket readily splits, leaving surfaces favorable for the application of glue when the same pneumatic, or a substitute pneumatic, is reapplied. This is a distinct advantage over a construction wherein two flat wooden surfaces are glued together, since such a joint is very difficult to open without splitting or breaking of the parts. Another advantage of locating the air channel 9 in the valve board resides in the fact that such a location of the air channel makes it possible to form and locate the valve motor diaphragm and its pressure and suction control ducts wholly in the removable stationary wall of the striker pneumatic, whereby each valve and its controls can readily be gotten at for inspection, repairs or renewals, by simply removing the striker pneumatic as a unit from the valve board 5 in the manner described. Also, should any of the bleed ducts 38 become clogged, they are readily gotten at and removed by simply taking out the plugs 32 without requiring any further dismantling of the structure.

I claim—

1. In a pneumatic player action, a valve board comprising an integral wooden structure hollowed out to provide valve chambers, ducts for connecting said valve chambers with striker pneumatics, and a continuous longitudinal air channel formed as a groove in one edge of said structure, and a closure strip glued to said edge to seal said air channel and forming an edge portion of said valve board. 120
2. In a pneumatic player action, a valve 130

- board comprising an integral wooden structure hollowed out to provide valve chambers, transversely disposed ducts on one side of said valve chambers for connecting the latter with striker pneumatics, and a continuous longitudinal air channel on the opposite side of said valve chambers formed as a groove in one edge of said structure, and a closure strip glued to said edge to seal said air channel and forming an edge portion of said valve board.
3. In a pneumatic player action, a valve board comprising an integral wooden structure of rectangular cross-section bored to provide round vertically disposed valve chambers and transversely disposed ducts on one side of said valve chambers for connecting the latter with striker pneumatics, and grooved in one edge to form a continuous longitudinal air channel on the opposite side of said valve chambers, and a closure strip of a width equal to the thickness of said structure glued to the grooved edge of the latter and forming an edge portion of said board.
4. In a pneumatic player action, a valve board comprising an integral wooden board bored to provide round vertically disposed valve chambers and transversely disposed ducts on one side of said valve chambers for connecting the latter with striker pneumatics, and grooved in one edge to form a continuous longitudinal air channel on the opposite side of said valve chambers, and a closure strip glued to the grooved edge of said board and formed with a tongue projecting into the open side of said air channel groove between the top and bottom walls thereof.
- 40 5. In a pneumatic player action, a valve board comprising an integral wooden structure hollowed out to provide valve chambers, ducts on one side of said valve chambers for connecting the latter with striker pneumatics, a continuous longitudinal air channel on the opposite side of said valve chambers, ducts in the bottom wall of said air channel for connecting the latter with the valve-actuating diaphragm of the striker pneumatics, and a closure strip sealing one side of said air channel.
6. In a pneumatic player action, the combination of a valve board containing valve chambers and an air channel extending along one side of said valve chambers, upper and lower valve seats in said valve chambers, valves in said valve chambers having their stems extending through the bottom of said valve board, and striker pneumatics each having a stationary wall of substantially triangular form in vertical longitudinal section attached to the under side of said valve board; each of said stationary sides formed with a suction chamber having a lateral extension registering with said air channel through the bottom of the latter and a pouch chamber, a valve-actuating pouch separating said chambers, a duct connecting said pouch chamber with a tracker tube through the thicker portion of said stationary wall, and a bleed controlled duct connecting said pouch chamber with said air channel through the thicker portion of said stationary wall.
7. In a pneumatic player action, the combination of a valve board containing a row of valve chambers substantially mid-width thereof, a longitudinally extending air channel on one side of said valve chambers, and transversely extending ducts communicating with the opposite sides of said valve chambers, and opening through one edge of said board, a strip glued to the said edge and sealing the outer ends of said transversely extending ducts, upper and lower valve seats in said valve chambers, valves in said valve chambers having stems extending through the bottom of said board, and striker pneumatics having their stationary sides attached to the under side of said valve board; each of said stationary sides formed with a suction chamber having a radial extension communicating with said air channel and a pouch chamber and ducts communicating one with a tracker tube and the other with a bleed vent to said air channel, a valve-actuating pouch separating said chambers, and a duct connecting a transversely extending duct of said valve board with the interior of the pneumatic.
